[57] CLAIM

The ornamental design for a fishing lure, as shown and described.

DESCRIPTION

FIG. 1 is a front elevational view of a design for a fishing lure embodying my invention; the attachments to said embodiment shown in dash dot lines are for illustrative purposes;

FIG. 2 is a top plan view thereof;

FIG. 3 is a bottom plan view thereof;

FIG. 4 is an end elevational view thereof; and

FIG. 5 is an opposite end elevational view thereof.
